PAIR OF SPECTACLES

Anthony Shindler, Brookline, Mass., assignor to American Optical Corporation, Southbridge, Mass.

Filed Dec. 9, 1970, Ser. No. 26,371

Term of patent 14 years

Int. Cl. D16—06

U.S. Cl. D57—1

FIG. 1

FIG. 2

FIG. 4

FIG. 3

FIG. 1 is a front elevational view of a pair of spectacles showing my new design;

FIG. 2 is a top plan view thereof, the temples being broken away for convenience of illustration;

FIG. 3 is a side elevational view thereof, the opposite side having the same appearance; and

FIG. 4 is a rear elevational view of the bridge of the spectacles, being fragmentarily shown for convenience of illustration.

I claim:

The ornamental design for a pair of spectacles, as shown and described.
